(57) **CLAIM**

The ornamental design for a mouth guide for use in registration of medical and dental imaging and other types of scanning modalities, as shown and described.

DESCRIPTION

FIG. 1 is a reduced top right end perspective view of a mouth guide for use in registration of medical and dental imaging and other types of scanning modalities showing our new design;

FIG. 2 is a left end elevation view thereof;

FIG. 3 is a right end elevation view thereof;

FIG. 4 is a top view thereof;

FIG. 5 is a bottom view thereof;

FIG. 6 is a front elevation view thereof; and,

FIG. 7 is a back elevation view thereof.
